SHEET-CUTTING MACHINE

Application filed March 8, 1928. Serial No. 260,179.

My invention relates to sheet cutting machines and more particularly to a machine for cutting rubber sheets at predetermined points as it is fed from the usual rubber sheet forming calendar.

An object of the invention is to provide a cutter whereby a length of sheet material will be severed in predetermined lengths.

Further the invention provides a rotary cutter which is adjustable to sever sheet material in desired uniform length and is also capable of adjustment to sever sheet material of various thicknesses.

With the preceding and other objects and advantages in mind, the invention consists in the novel combination of elements, constructions and arrangements of parts to be hereinafter specifically referred to, claimed and illustrated in the accompanying drawings, wherein:

Figure 1 is a view partly in elevation and partly in longitudinal section of my invention;

Figure 2 is a top plan view of the same;

Figure 3 is a vertical sectional view taken on line 3—3 of Figure 1;

Figure 4 is a perspective of the rotary cutting knife embodied in the invention; and

Figure 5 is a detail sectional view illustrating a different pinion ratio from that disclosed in Figure 1.

Referring to the invention in detail a pair of horizontally disposed parallel rollers 5, about which an endless belt 6 is trained, is 35 journaled in upstanding parallel legs 7. The endless belt is arranged to receive and carry sheet material such as a rubber sheet S from a conventional rubber sheet forming calendar 8 arranged in close proximity to one of the rollers 5.

Arranged upon opposite sides of the endless belt and between the parallel rollers is a pair of parallel vertical standards 9, the latter extending above the endless belt and having supporting feet 10 at their lower ends. To pro-

vide a bearing or support for the sheet material while it is being severed, a horizontally disposed roller 11, located in horizontal alinement with the rollers 5 and over which the endless belt passes, is journalled in the vertical standards. At one end this roller is formed with a projecting shaft 12, carrying a drive pinion 13 adjacent its outer end and operatively engaged by oppositely extending sprocket chains 14 and 15, respectively, the former engaging the roller 5 at one end of the belt, and the latter operatively engaging the other roller. Power is supplied to the rollers 5 and 11 by means of a sprocket chain 16 engaging one of the rotatable parts of the calendar and the adjacent roller 5.

In order to sever the sheet S into predetermined uniform lengths, a rotary knife blade 17 is mounted above the bearing roller for cooperation therewith in severing the sheet material. For the purpose of rotatably supporting the knife blade it is attached to one face of a horizontally disposed bar 18, extending transversely across the endless belt in vertical alinement with the bearing roller, and is formed with oppositely extending stub shafts 19, one of which carries a pinion 20 at one end meshing with the drive pinion 13.

The diameter of the pinion 20 determines the length of the material to be cut. That is to say, the knife blade is brought into severing relation to the sheet material and bearing roller each complete revolution of the pinion 20. It therefore follows that the length of each piece of material severed is equal in length to the circumference of this pinion. The invention therefore proposes to govern the length of the cut by the employment of a plurality of pinions 20 of various diameters. To permit interchanging of the pinion 20, the latter is removably held to its stub shaft by a removable nut 21 threaded on the latter.

To compensate for the variance in the diameters of the pinions 20 it is necessary to

mount the bar 18 for vertical adjustment so that the cutting edge of the knife blade will penetrate the sheet material. For this purpose the stub shafts 19 are journalled in blocks or bearings 22 vertically movable in parallel vertical slots 23 provided in the standards 9. To adjust the blocks vertically, a vertically disposed screw 24 is swivelled at its lower end to the upper face of each of the blocks, as at 10 25. These screws are vertically movable through pairs of parallel ears 26 projecting laterally from the inner face of the standards at their upper ends, and are engaged with internally threaded worm gears 27 held 15 against vertical displacement by each pair of ears. A horizontally disposed worm shaft 28 carrying a hand wheel 29 at one end is journalled in the upper ends of the standards and engages the worm gears. It will be observed that upon rotation of the hand wheel the 20 worm gears will be rotated to feed the screws 26 therethrough, and consequently raise or lower the blocks 22 in synchronism.

To adjust the knife blade relative to the 25 bar 18 to dispose its cutting edge in cutting relation to the sheet material regardless of the diameter of the pinion 20, the knife blade is provided with a plurality of parallel transverse slots 30 through which adjustable fastenings 31, engaging the bar, pass.

It will be manifest that the knife blade will be raised or lowered relative to the bar 18, depending upon the diameter of the pinion 20, employed.

35 In addition to severing the sheet material transversely by the rotatable knife blade, the sheet material is cut longitudinally by means of a gang of circular cutting knives 32 fixed to a horizontally disposed transverse shaft 33 arranged above the endless belt and supported in parallel brackets 34 extending forwardly from the standards. To drive the shaft 33 a sprocket chain 35, engaging the shaft 12, engages this shaft 33.

45 In the operation of the invention the sheet rubber or other material is advanced longitudinally over the bearing roller by means of the endless belt and at the same time the knife blade approaches the sheet material at 50 a tangent with respect to the periphery of the bearing roller, the sheet material is pinched or severed between the periphery of this roller and the cutting edge.

What is claimed is:—

55 1. In combination a rotatable work support, a conveyor movable thereover for moving sheet material in a longitudinal direction, a rotary knife supported above the work support and cooperating therewith in 60 severing the sheet material in uniform lengths, and means for determining the length of the cut of the sheet material.

2. In a cutter for severing sheet material, a roller supported in a horizontal plane over 65 which sheet material is fed in a longitudinal

path, a vertically adjustable horizontal shaft journalled above the roller, a knife blade carried thereby and mounted for vertical adjustment thereon, and intermeshing pinions on the roller and shaft, one of which determining the length of the severed pieces of sheet material. 70

3. In a cutter for severing sheet material, a roller supported in a horizontal plane over which sheet material is fed in a longitudinal path, a vertically adjustable horizontal shaft journalled above the roller, a vertically adjustable knife blade carried thereby, intermeshing pinions on the roller and shaft, one of which determining the length of the severed pieces of sheet material, and means for adjusting the shaft towards and away from the roller to permit a pinion of predetermined diameter to be utilized on one of such rotating parts. 80

4. In a sheet material cutting machine, a horizontally disposed roller over which sheet material is fed in a longitudinal path, a horizontal shaft above the roller capable of vertical adjustment, a vertically adjustable knife blade attached thereto, and a driven element of a predetermined diameter removably carried by the shaft whereby to cause the knife to sever the sheet material at predetermined points. 95

5. In combination a support over which sheet material is advanced longitudinally, a vertically adjustable transverse shaft above the support, a vertically adjustable knife blade projecting at right angles from the shaft and cooperating with the support in severing the sheet material as it is advanced. 100

6. In combination a support over which sheet material is advanced longitudinally, a vertically adjustable transverse shaft above the support, a vertically adjustable knife blade projecting at right angles from the shaft and cooperating with the support in severing the sheet material as it is advanced, and manually operable means for raising and 110 lowering the shaft. 105

7. In combination a horizontal roller over which sheet material is advanced in a longitudinal direction and carrying a drive pinion, a horizontal shaft above the roller and adjustable towards and away from the same, a knife carried by the shaft and mounted for vertical adjustment, a driven pinion detachable from the shaft and meshing with the drive pinion, the shaft being adjusted away from the roller to permit a different driven pinion to be substituted for the first, and manually operable means for adjusting the shaft. 115

8. In combination a horizontal roller over which sheet material is advanced longitudinally and carrying a drive pinion, a vertical adjustable horizontal shaft above the roller, a driven pinion detachable from the shaft and meshing with the drive pinion, manually operable means for adjusting the shaft to per- 125 130

- mit a drive pinion of different diameter to be associated with the shaft, a knife blade projecting at right angles from the shaft and cooperating with the roller in severing the sheet material as the latter is advanced, and
 5 means for adjusting the knife blade relative to the shaft to dispose its cutting edge in cutting relation to the sheet material regardless of the diameter of the driven pinion.
9. In a rotary cutter, a horizontal bearing roller over which sheet material is fed in a longitudinal path, a horizontal shaft above the bearing roller, a cutting blade vertically adjustable on the shaft, a driven pinion removably mounted on the shaft for which a pinion of different diameter may be substituted, a drive pinion with which the driven pinion meshes, vertically adjustable bearings in which the shaft is journalled, a screw swivelled to each bearing, and means
 10 for feeding the screws vertically whereby to adjust the shaft to a predetermined height to permit a driven pinion of predetermined diameter to be associated with the shaft.
- 15 10. In a rotary cutter, a horizontal bearing roller over which sheet material is fed in a longitudinal path, a horizontal shaft above the bearing roller and driven from the latter, a cutting blade carried thereby and cooperating with the bearing roller in severing the sheet material each complete revolution of the shaft, vertically adjustable bearings in which the shaft is journalled, a screw swivelled to each bearing, and internally threaded elements receiving the screws and geared together for unitary rotation whereby to feed both screws simultaneously to adjust the cutter shaft with relation to the various size gears, and means for adjusting the knife blade
 20 relative to the shaft to dispose its cutting edge in cutting relation to the sheet material regardless of the height of the shaft.
- 25 11. In a rotary cutter, a horizontal bearing roller over which sheet material is fed in a longitudinal path, a drive pinion carried thereby, a longitudinal shaft above the bearing roller, a cutting blade vertically adjustable on the shaft, of drive pinion adapted to be removably mounted on the shaft and
 30 mesh with the drive pinion, a cutting blade carried thereby and cooperating with the bearing roller in severing the sheet material upon each complete revolution of the shaft, vertically adjustable bearings in which the
 35 shaft is journalled, a vertically arranged screw swivelled to each bearing and internally threaded elements receiving the screws and geared together for unitary rotation whereby to feed both screws simultaneously to adjust
 40 the shaft to a predetermined elevation so that a driven pinion of predetermined diameter may be mounted on the shaft and mesh with the driven drive pinion.
- 45 12. A machine for severing sheet material having, in combination, a belt conveyer for
 50 sheet material, a rotary drum constituting a support for said conveyer, a straight cutter blade extending transversely of said conveyer belt and longitudinally of said drum, the cutting edge of said cutter blade adapted to engage one face of said conveyer belt with
 55 the conveyer belt interposed between said cutter blade and the drum.
